SET OF BATH TREADS

John R. Howard, Lombard, Ill., assignor to Minnesota
Mining and Manufacturing Company, St. Paul, Minn.

Continuation-in-part of abandoned design application Ser.
No. 173,733, Aug. 20, 1971. This application Feb. 7,
1972, Ser. No. 224,380

Term of patent 14 years

Int. Cl. D6—11

U.S. Cl. D6—209

FIG. 1

FIG. 2

FIG. 3

FIG. 1 is a top plan view of a set of bath treads showing my new design with the units of the set arranged in a position of use;

FIG. 2 is a side elevational view thereof; and

FIG. 3 is an end elevational view thereof.

This is a continuation-in-part of my copending application Ser. No. 173,733, filed Aug. 20, 1971, and now abandoned.

I claim:

The ornamental design for a set of bath treads, substantially as shown and described.
